TELEVISION RECEIVER OR SIMILAR ARTICLE

Joseph Horzick, West Chicago, Ill., assignor to Motorola,
Inc., Franklin Park, Ill., a corporation of Illinois

Filed Jan. 14, 1970, Ser. No. 20,915

Term of patent 14 years

Int. Cl. D14—03

U.S. Cl. D56—4

FIG.1

FIG.2

FIG.3

FIG.4

FIG. 1 is a front, top and right side perspective view of a television receiver or similar article, showing my new design;

FIG. 2 is a rear, top and left side perspective view; FIG. 3 is a right side, top and rear perspective view;

FIG. 4 is an enlarged fragmentary cross-sectional view taken along the line 4-4 in FIG. 3;

FIG. 5 is an enlarged fragmentary right side elevational view; and

FIG. 6 is an enlarged fragmentary front elevational view thereof.

Portions of the drawing figures are diagonally lined to indicate transparency.

I claim:

The ornamental design for a television receiver or similar article, as shown and described.
